LOOSE POWDER CONTAINER

Filed Sept. 4, 1928

FIG. 1

FIG. 2

FIG. 3

Inventor

James Leslie Younghusband

By Charles F. Sill Atty

UNITED STATES PATENT OFFICE

JAMES LESLIE YOUNGHUSBAND, OF CHICAGO, ILLINOIS

LOOSE-POWDER CONTAINER

Application filed September 4, 1928. Serial No. 303,636.

This invention relates to a container for loose cosmetic powder.

An object of the invention is to provide a container or compact for loose powder having a flanged opening to the powder compartment wherein the powder puff or applicator forms a closure for the powder compartment.

Another object of the invention is to provide a loose powder container having a double flange member in which one of the flanges serves as the top of the powder compartment and the other as a shoulder for retaining the applicator in position to close the opening to the powder container.

A further object is to provide a loose powder container having a flanged opening, the member forming the flange consisting of a double flange structure formed from a single piece of sheet metal, with one of the flanges serving as a part of the powder compartment and defining an opening thereto and the other flange cooperating with the first for retaining the applicator in position to close the opening.

A further object is to provide a double flange member for loose powder containers which is economical to manufacture and efficient in use.

The above, other and further objects of the invention will be apparent from the following description, accompanying drawings and appended claims.

According to the invention, a loose powder container has a receptacle for loose powder, with a flanged opening therefor, which flange is formed for a single sheet of metal into substantially U-shape in cross section, with the flanges directed inwardly and substantially parallel, the inner openings of the flanges permitting access to the powder, and an applicator retained between the two flanges.

One form of the invention is illustrated in the accompanying drawings and the views thereof are as follows:

Figure 1 is a front elevational view of a container having a hinged top and embodying the invention.

Figure 2 is a top plan view of the container wide open for use.

Figure 3 is an enlarged vertical section through the powder receptacle.

The container illustrated comprises a bottom member 1 and a top member 2 which in the present instance are shown as hinged at 3. I do not wish to be limited to the hinged construction of the members 1 and 2 as containers or compacts may be made with these two parts separate.

The bottom or receptacle 1 may be made of metal, bakelite, ivory, or any other suitable material, and as illustrated comprises a dished bottom 4 with a marginal circular wall 5 integral with the bottom. The upper portion of the marginal wall 5 is shouldered as at 6 to receive the margin of the top member 2 when closed.

A flange is frictionally retained within the wall 5 of the receptacle and comprises a lower flange 7, an upper flange 8 and a common peripheral wall 9, the flanges and wall being made from a single sheet or strip of metal. The lower flange 7 defines a central opening 10 which is the opening to the powder compartment 11. The upper flange 8 has a central opening somewhat larger in diameter than the opening 10 in the lower flange.

An applicator 12 is retained between the flanges 7 and 8 to close the opening 10 and thus prevents spillage of the powder from the receptacle. The diameter of the applicator 12 is larger than the diameter of the upper flange 8 so that a slight spring action takes place when the applicator is applied to or removed from the position shown in the drawings.

The applicator 12 has the usual handle 13.

I have shown a perforated cover or sieve 14 overlying the powder opening 10. The applicator 12 rests on this sieve when the same is used, though the use of the sieve is optional.

The flange member is frictionally retained within the wall 5 of the receptacle near the top thereof so as to provide a powder compartment of maximum capacity.

The top 2 has a mirror 15 retained therein by a flange 16. A projection 17 is formed

on the top 2 for an aid in opening said top.

It will be observed that the applicator 12 is retained in position to prevent escape of the powder even when the top 2 is removed by 5 being retained between the flanges 7 and 8.

The shape of the receptacle may, of course, be varied beyond that shown and described, in which event the flange member would be made to correspond to the contour of the receptacle.

10 While I have described more or less precisely the details of construction of my invention, yet I do not wish to be understood as limiting myself thereto as I am aware that changes may be made in the arrangement 15 and proportion of parts and that equivalents may be substituted, all without departing from the spirit and scope of my invention.

I claim as my invention:

20 1. A container for loose powder comprising top and bottom members, one of said members arranged to receive the powder and the other of said members arranged to carry a mirror, a circular member having parallel spaced inwardly directed flanges frictionally engaging the wall of said powder receiving member to form therewith a powder compartment, one of said flanges being wider than the other and being disposed below said other when in 25 position, and an applicator retained between said flanges by spring action.

2. A container for loose powder comprising top and bottom members, one of said members arranged to receive the powder and 30 the other of said members arranged to carry a mirror, a circular member having parallel spaced inwardly directed flanges frictionally engaging the wall of said powder receiving member to form therewith a powder compartment, one of said flanges being wider than the other and being disposed below said other when in position, an applicator retained between said flanges by spring action, and a sieve supported on said lower flange overlying the opening through the same and underlying said applicator.

35 3. A container for loose powder comprising top and bottom members, one of said members comprising a receptacle to receive powder, a circular member substantially U-shaped in section with the flanges of different widths and horizontally disposed in said receptacle for providing therewith a powder compartment having a central opening, said member being frictionally retained within said receptacle, the diameter of the central opening of the lower flange being less than the diameter of the central opening of the upper flange, and an applicator engaging 40 underneath said upper flange and held thereby against the opening in the other flange to close the same.

4. A container for loose powder comprising top and bottom members, one of said 45 members comprising a receptacle to receive

loose powder, a circular flange member formed from a single sheet of metal by bending the same into substantially U-shape and made with the flanges substantially parallel and horizontally disposed, the peripheral portion frictionally engaging the receptacle wall and forming a powder compartment therewith and defining an opening to said compartment, and an applicator retained between said flanges for closing said opening.

5. A container comprising a receptacle, and a member comprising a portion engaging the inner wall of the receptacle and terminating in spaced parallel inwardly extending flanges defining the opening into said receptacle and a material compartment therein with the opening defined by the upper flange of greater size than the opening defined by a lower flange.

6. A container comprising a receptacle, a member comprising a portion engaging the inner wall of the receptacle and terminating in spaced inwardly extending flanges, the upper flange of which defines a larger opening into the receptacle than that defined by the lower into the material compartment in said receptacle.

In testimony whereof I have hereunto subscribed my name at Chicago, Cook County, Illinois.

JAMES LESLIE YOUNGHUSBAND.
